SWINGING SCAFFOLD

Rolph J. Lackner, Richmond Hill, N. Y., assignor
to Emma H. Lackner, Richmond Hill, N. Y.

Application August 1, 1946, Serial No. 687,730

8 Claims. (Cl. 304—19)

1

This invention relates to improvements in swinging scaffolds as disclosed in Patent No. 1,488,822 issued to me April 1, 1924.

Manufacture and use of the patented structure has taught the advisability of structural simplification, and also, as well as more important perhaps, safe-guard, in so far as possible, against carelessness and incomprehension involved on the part of workmen using the scaffold.

The objects of the present improvements are, therefore, to simplify the structure of the original device, to provide an arrangement wherein, even an untutored workman may not through carelessness or inadvertence, blunder into a mistake in the use of the scaffold which may, through accidental breaking of the ropes at either one end or the other of the platform of the scaffold, cost him his life, wherein rope clamps each embodying a single movable jaw will be provided in connection with the strands of ropes at each end of said platform, wherein an adjustable connecting rod will be provided between each end of the platform and the movable jaw of the adjacent clamp so that, in the event a strand of the rope at either end of the platform should break, the tilting throw of the platform necessary to actuate the movable jaw of either clamp may be determined in advance at the time the scaffold is first erected, wherein the upward movement of one end of the platform caused by the downward movement of the other end thereof will not open the movable jaw at the high end of the platform, and wherein the strands of the ropes will be partitioned at the clamps so as not to become entangled.

Other and incidental objects will appear during the following description of the invention, and in the drawings:

Figure 1 is a front elevation of my improved scaffold.

Figure 2 is a detail perspective view of one of the rope clamps.

Figure 3 is a plan view of the clamp, the strands of the coacting rope being shown in section.

Figure 4 is an end elevation.

Figure 5 is a horizontal section.

Figure 6 is a vertical section.

Figure 7 is a detail perspective view of one of the connecting rods employed, the sections of the rod being shown separated.

Referring now more particularly to Figure 1 of the drawings, I employ the usual platform 10 having rungs 11 supporting a floor 12. Conventional stirrups 13 embrace the platform and are

provided at their upper ends with eyes 14 as well as with the usual loops 15 which latter removably receive a guard rail 16. Beams 17 project over the roof or other portion of the building against which the scaffold is erected, as will be well understood, and detachably connected therewith are upper pulley blocks 18 which receive ropes 19 trained about lower pulley blocks 20, the usual hooks 21 of which latter are detachably engaged through the eyes 14 of the stirrups 13 for supporting the platform 10 suspended. In practice, the free strand of each of the ropes 19 is given a tie-knot about the adjacent hook 21 for securing the platform 10 at any given elevation, as will also be well understood.

Now taking up the present improvements in detail, it may be noted that the structure shown at the right and left of Figure 1 duplicates each other. For the sake of clarity, I will therefore, 20 in describing the structure, refer to a single block 20 only, and associated parts.

A conventional block may be employed, in which event, I attach to the sheath thereof an upstanding lug 22, or the sheath and lug may, 25 if so desired, be formed for the purposes of the present invention as an integral structure. Fixed to the lug 22 is a rope clamp, now to be described.

As perhaps best shown in Figure 2, the rope clamp includes a straight shank 23 suitably fixed 30 to the lug 22, or, if preferred, the shank may be formed as an integral continuation of the sheath of the pulley block. The shank 23 is offset near its upper end and provided with an overhanging yoke 24 having parallel arms 25. Extending laterally from the shank at the offset thereof is an integral fixed jaw 26 from which extend spaced fingers 27.

Pivoted upon the yoke 24 is a movable jaw 28 confronting the fixed jaw 26 to coact therewith. 40 If so desired, the confronting faces of either or both jaws may be serrated to better grip the strands of a rope extending therebetween. Formed on the jaw 28 midway between the ends thereof is a lateral arm 29, and rising from said arm are spaced lugs 30 fitting between the arms 25 of the yoke 24.

Extending forwardly and downwardly from between the lugs 30 of the arm 29 is a more or less L-shaped operating lever 31 provided at its free end with a lateral terminal 32, and extending through the free ends of the arms 25 of the yoke 24, through the lugs 30 of the arm 29, and through the inner end of the lever 31 is a removable pivot bolt 33, preferably provided with a wing nut 34 55 so that the bolt may be readily removed by hand.

Engaged through the free end of the arm 29 to coact with the lower edge of the lever 31 near its inner end is a set screw 35.

Preferably, the ends of the jaw 28 are channeled, and detachably fixed in the channels thereof are end fingers 36 preferably secured by clamp screws 37. Thus, the fingers 27, which extend over the jaw 28, in conjunction with the fingers 36 and yoke 24 will partition the space between the jaws 26 and 28 so that, as seen in Figures 3 and 5, the strands of the coacting rope 19 may not become entangled at the rope clamp.

Extending between the operating lever 31 and the adjacent end of the platform 10 is a connecting rod, indicated as a whole at 38. Preferably, this rod is formed of two sections 39 and 40 respectively, and while, casually, the rod might be considered as a mere reach rod still, in the present instance, the structural details thereof render it distinctive.

The section 39 of the rod 38 is formed at one end with a yoke 41, while at the other end of said section are provided ears 42. Formed in the section longitudinally thereof are spaced openings 43. The section 40 is likewise provided with spaced openings 44, and at one end of said section is a yoke 45. The openings 44 are of the same size as the openings 43, and the two sections are assembled end to end flat against each other to receive a bolt 46 entering through matching openings in the sections and preferably provided with a wing nut 47 so that the sections may, as will be at once appreciated, be positioned relative to each other and clamped together by the bolt 46 and nut 47 for adjusting the length of the rod as a whole. In such position of the sections, the ears 42 will embrace the section 40 to cooperate with the bolt 46 and hold the sections in alignment. However, the presence of the ears 42 is not imperative.

The yoke 41 of the section 39 of the rod 38 is detachably connected to the terminal 32 of the lever 31 by a bolt 48 and wing nut 49. Detachably fixed to the adjacent end rung 11 of the platform 10 is a collar 50, and detachably connecting the yoke 45 of the section 40 of the rod 38 with said collar is a bolt 51 and wing nut 52.

It is now to be noted that the bolts 46, 48, and 51 are all of the same size, as are the openings which receive them. Consequently, since conventional stirrups 43 vary in over-all height, both sections 39 and 40 may be used for a long stirrup while, for a short stirrup, only one of the sections may be employed to extend between the free end of the lever 31 and the collar 50.

In this connection, the importance of the adjustment in the connection between the platform 10 and the lever 31 should be noted. As will be perceived, if one of the strands of the rope 19, say at the left of Figure 1, should break, the adjacent end of the platform 10 will move down and act on the rod 38 to pull the lever 31 downwardly. Thus, the lever will act on the screw 35 to rock the movable jaw 28 toward the fixed jaw 26, with the result that the strands of the rope will be clamped between the jaws to check further downward movement of said end of the platform so that the platform will be automatically prevented from swinging to vertical position.

As will be seen, the length of travel of the movable jaw 28 under the foregoing conditions may, by varying the length of the rod 38, be roughly adjusted before the platform is erected while, concurrently, the screw 35 may be turned to obtain a finer adjustment. Thus, the throw of said lever

and, consequently, the downward throw of said end of the platform necessary to clamp the rope strands between the jaws may be regulated and determined in advance.

5 To disassemble the structure, the rod 38 is detached when, if so desired, the sections 39 and 40 of the rod may be detached from each other. The lever 31 is then detached and turned end for end, when the terminal 32 thereof is secured by the bolt 33 between the lugs 30 of the arm 29. The lever will then hang substantially parallel to the associated jaw assembly and to the adjacent pulley block to afford compactness.

Referring now again to Figure 1 of the drawings, it will be at once appreciated in view of the foregoing description that if one of the strands of either of the ropes 19 should break, the adjacent end of the platform 10 will be permitted to tilt downwardly only a predetermined distance so that the safety of workmen on the platform will be assured. Furthermore, as will be perceived, downward movement of one end of the platform 10 with consequent upward movement of the other end thereof, will result only in the movement, at the high end of the platform, of the adjacent lever 31 upwardly away from the set screw 35 of the rope clamp at the high end of the platform, so that the normal position of the movable jaw 28 relative to the fixed jaw 26 of said clamp 30 will not be affected.

Having thus described my invention, what I claim is:

1. A safety device for swinging scaffolds including a fixed jaw and a movable jaw disposed at opposite sides of the scaffold suspending rope and normally free thereof, a pivoted lever movable upwardly away from the movable jaw independently thereof and downwardly to operatively coact with said movable jaw for rocking the same 40 toward the fixed jaw to clamp said rope therebetween, means for supporting said jaws from a pulley block of the scaffold, and a connection between the free end of said lever and an end of the scaffold platform whereby dropping of said 45 end of the platform will cause actuation of the movable jaw to grip the suspending rope between said jaws.

2. A safety device for swinging scaffolds including a fixed jaw and a movable disposed at 50 opposite sides of the scaffold suspending rope and normally free thereof, a pivoted lever movable upwardly away from the movable jaw independently thereof and downwardly to operatively coact with said movable jaw for rocking the same toward the fixed jaw to clamp said rope therebetween, means for supporting said jaws from a pulley block of the scaffold, and a connection of 55 linearly adjustable sections between the free end of said lever and an end of the scaffold platform whereby dropping of said end of the platform will cause actuation of the movable jaw to grip the suspending rope between said jaws.

3. A safety device for swinging scaffolds including a fixed jaw and a movable jaw disposed at 60 opposite sides of the scaffold suspending rope and normally free thereof, a pivoted lever movable upwardly away from the movable jaw independently thereof and downwardly to operatively coact with said movable jaw for rocking the same toward the fixed jaw to clamp said rope therebetween, means carried by the movable jaw for engagement by said lever and adjustable for changing the normal position of the lever relative to the movable jaw, means for supporting said 65 jaws from a pulley block of the scaffold, and a

connection between the free end of said lever and an end of the scaffold platform whereby dropping of said end of the platform will cause actuation of the movable jaw to grip the suspending rope between said jaws.

4. A safety device for swinging scaffolds including a fixed jaw and a movable jaw disposed at opposite sides of the scaffold suspending rope and normally free thereof, a pivoted lever movable upwardly away from the movable jaw independently thereof and downwardly to operatively coact with said movable jaw for rocking the same toward the fixed jaw to clamp said rope therebetween, means for supporting said jaws from a pulley block of the scaffold, a single means pivotally connecting the movable jaw and said lever with said supporting means, and a connection between the free end of said lever and an end of the scaffold platform whereby dropping of said end of the platform will cause actuation of the movable jaw to grip the suspending rope between said jaws.

5. A safety device for swinging scaffolds including a fixed jaw and a movable jaw disposed at opposite sides of the scaffold suspending rope and normally free thereof, a pivoted lever movable upwardly away from the movable jaw independently thereof and downwardly to operatively coact with said movable jaw for rocking the same toward the fixed jaw to clamp said rope therebetween, means for supporting said jaws from a pulley block of the scaffold and including a yoke, a bolt pivotally connecting the movable jaw and said lever with said yoke, and a connection between the free end of said lever and an end of the scaffold platform whereby dropping of said end of the platform will cause actuation of the movable jaw to grip the suspending rope between the jaws.

6. A safety device for swinging scaffolds including a fixed jaw and a movable jaw disposed at opposite sides of the scaffold suspending rope and normally free thereof, a pivoted lever movable upwardly away from the movable jaw independently thereof and downwardly to operatively coact with said movable jaw for rocking the same toward the fixed jaw to clamp said rope therebetween, means for supporting said jaws from a pulley block of the scaffold, companion rod sections forming a connection between the free end of said lever and an end of the scaffolding plat-

form whereby dropping of said end of the platform will cause actuation of the movable jaw to grip the suspending rope between said jaws, a bolt adjustably connecting said sections with each other, and ears carried by one of the sections to engage the other of said sections locking the sections in alignment.

7. A safety device for swinging scaffolds including a fixed jaw and a movable jaw disposed at opposite sides of the scaffold suspending rope and normally free thereof, a pivoted lever movable upwardly away from the movable jaw independently thereof and downwardly to operatively coact with said movable jaw for rocking the same toward the fixed jaw to clamp said rope therebetween, means for supporting said jaws from a pulley block of the scaffold and including a shank fixed to said block and having said fixed jaw thereon as well as being provided with a yoke, lugs on the movable jaw mating with said yoke and receiving the inner end of said lever therebetween, means extending through the yoke, said lugs and the lever pivotally connecting the movable jaw and said lever with said yoke, an arm extending from the movable jaw, a set screw engaged through said arm to abut the inner end portion of said lever and adjustable for changing the normal position of said lever relative to the movable jaw, and a connection between the outer end of said lever and an end of the scaffold platform whereby dropping of said end of the platform will cause actuation of the movable jaw to grip the suspending rope between said jaws.

8. A safety device for swinging scaffolds including a fixed jaw and a movable jaw disposed at opposite sides of the scaffold suspending rope and normally free thereof, a pivoted lever movable upwardly away from the movable jaw independently thereof and downwardly to operatively coact with said movable jaw for rocking the same toward the fixed jaw to clamp said rope therebetween, means for supporting said jaws from a pulley block of the scaffold, a connection between the free end of said lever and an end of the scaffold platform whereby dropping of said end of the platform will cause actuation of the movable jaw to grip the suspending rope between said jaws, and fingers carried by both jaws and disposed to partition the space therebetween separating the strands of said rope.

ROLPH J. LACKNER.
